US00D802852S

(12) **United States Design Patent** (10) **Patent No.:** **US D802,852 S**
Baker et al. (45) **Date of Patent:** **** Nov. 14, 2017**

(54) **BOTTLE**

(71) Applicant: **Doskocil Manufacturing Company, Inc.**, Arlington, TX (US)

(72) Inventors: **Nicholas Baker**, Fort Worth, TX (US); **Vas Obeyesekere**, Seattle, WA (US)

(73) Assignee: **DOSKOCIL MANUFACTURING COMPANY, INC.**, Arlington, TX (US)

(**) Term: **15 Years**

(21) Appl. No.: **29/548,240**

(22) Filed: **Dec. 11, 2015**

(51) LOC (10) Cl. **30-03**

(52) U.S. Cl. USPC **D30/132**; D9/516; D9/549; D9/563; D9/774; D7/300

CLAIM

The ornamental design for a bottle, as shown and described.

DESCRIPTION

FIG. 1 is a front perspective view of a bottle in accordance with our new design;

FIG. 2 is a front view of the bottle in accordance with our new design of FIG. 1;

FIG. 3 is a rear view of the bottle in accordance with our new design of FIGS. 1 and 2;

FIG. 4 is a side view of the bottle in accordance with our new design of FIGS. 1 to 3;

FIG. 5 is a side view of the bottle in accordance with our new design of FIGS. 1 to 4; and,

FIG. 6 is a top plan view of the bottle in accordance with our new design of FIGS. 1 to 5.

The broken lines depict environmental subject matter, are for illustration only, and form no part of the claimed design.

1 Claim, 6 Drawing Sheets
